UNITED STATES PATENT OFFICE.

WILLIAM W. FELTER, OF ARKANSAS CITY, KANSAS.

FORMING-CLAMP FOR TWO-PIECE SNOW-SHOES.

1,352,362.

Specification of Letters Patent.

Patented Sept. 7, 1920.

Application filed December 19, 1919. Serial No. 345,966.

To all whom it may concern:

Be it known that I, WILLIAM W. FELTER, a citizen of the United States, residing at Arkansas City, in the county of Cowley and State of Kansas, have invented new and useful Improvements in Forming-Clamps for Two-Piece Snow-Shoes, of which the following is a specification.

This invention relates to clamps for shaping the frames of snow shoes and the principal object of the invention is to provide means for turning up the toe of the shoe and holding it in this position while drying.

Another object of the invention is to provide means for holding the body of the frame in position on the base of the clamp which is provided with a forming block and adjustable means for forcing the heel part of the frame together.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a side view of the invention.

Fig. 2 is a top view.

Fig. 3 is a section on line 3—3 of Fig. 1.

Fig. 4 is a section on line 4—4 of Fig. 2.

Fig. 5 is a detail view of one of the toe forming blocks.

Fig. 6 is a view of the snow shoe frame formed by my invention.

The snow shoe for which my device is intended is of the shape shown in Fig. 6 and is composed of the two side pieces A and B which are bowed outwardly and have their ends connected together. The ends at the toe part of the shoe are bent upwardly as shown.

I prefer to form the device so it may form a pair of shoes and in order to do this I provide a base board 1 which is provided with shoe holding means on each face thereof. As the means on one face are similar to those on the other only one set of these means will be described in detail. A forming block 2 is secured to the base with its side edges curved slightly to bow the strips

of the shoe, these strips engaging the curved edges. The strips are held on the base by the turn buttons 3 which are held to the base by bolts or the like. The heel end of the shoe is engaged by the recessed block 4 and the heel portions of the strips are pressed together by the adjustable blocks 5 which pass through openings 6 in the base and are adjusted by the bolts 7 passing through the edges of the base and entering the openings. Pins 8 pass through the blocks and hold them in the openings. These blocks extend beyond each face of the base and act upon both shoes.

The means for bending the toe part of the strips upwardly consists of a block 9 having a curved part 10 which is preferably provided with small bars 11 of metal or the like embedded in its surface and adapted to engage the strips of the shoe. A handle 12 is connected with said block and a small block 13 having a recess 14 therein is bolted to the block 9 on its curved face. A curved strip of metal 15 of tapered formation has its small end passing through the recess 14 in block 13 and bent over and clamped to said block by the metal plate 16, which is held to the block by the bolts which hold said small block to the large block. The curve of this strip 15 follows the curve of the large block but is spaced therefrom so as to receive the strips of the snow shoe between itself and the large block when the ends of the strip are placed in the recess 14. A recessed strip 17 is secured to the outer face of the large block. The recess 17 in this strip registers with the recess 14 in block 13 and acts as a stop for the ends of the strips of the shoe.

After the strips are softened by being treated with steam or the like their heel parts are placed in the recess in the block 4 and between the adjustable blocks 5. The strips are then bent around the forming block 2 and the buttons turned to hold the strips on the base. The bolts 7 are then turned to force the adjustable blocks toward each other to bring the heel parts of the strips into contact. A wedge piece 18 may then be driven in the recess in block 4 to hold said heel parts in position. The toe ends of the strips are then pressed together and passed into the recess 14 in block 13, the metal strip 15 being bent outwardly to permit the strips to pass into said recess. It

will be understood that the block 9 and the strip 15 are not attached to the base but are free, the block being placed by hand in engagement with the ends of the strips to be bent with the metal strip 15 placed under said strips A and B between the same and the base so that the strips A and B have their ends located between the metal strips 15 and the block 9. The handle 12 of block 9 is then moved over in the direction of the base to give a turning movement to said block 9 and this movement will turn the toe ends of the strips upwardly as shown, the metal strip 15 following the movement of these ends so that the ends are held between the curved face of the block 9 and said strip. After the handle is moved downwardly as far as possible it may be connected with the base by means of the bolt 19 or in any other desired manner. A weight 20 may be attached to the handle by a flexible connection 21 which passes over the outer face of the block 9 to prevent the front part of the strips from leaving the base. When the strips have dried in the clamp they may be removed by loosening the bolts connecting the small block 13 with the block 9 to permit said block 9 to be removed from the turned ends of the shoe. Then the turn buttons are turned to release the body of the shoe and then said body is released from the adjustable blocks so that it may be lifted from the base. The strips are then ready to be connected together and to receive the filler. It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A device of the class described comprising a base having a slot therein, a block on each face of the base having a recess therein for receiving the heel ends of a pair of snow shoe strips, a former block on each face of the base for holding the strips in position, a pair of heel engaging blocks adjustably mounted in the slot and having their ends engaging both pairs of the strips and means for bending the toe ends of each pair of strips upwardly and holding them in this position. 50
2. A device of the class described comprising a base, means thereon for holding the snow shoe strips in position and means separate from the base for curving the toe ends of the strips, such means consisting of a block having a curved face, a handle connected with the block for manually manipulating the same, means for securing the handle to the base after the ends are curved, a stop strip on the top of the block having a recess therein for receiving the extremity of the snow shoe strips and a recessed member on the curved face of the block for receiving the end portions of the snow shoe strips. 55
3. A device of the class described comprising a base, means for holding the snow shoe strips thereon, a block and handle for curving the ends of said strips, said block and handle being separate from the base when curving the ends, means for securing the said parts to the base after the ends are curved, a recessed member on the curved face of the block for receiving the ends of the strips and a metal strip carried by said recessed member in spaced relation to the curved end of the block and engaging the under edges of the strips. 70 80

In testimony whereof I affix my signature.
WILLIAM W. FELTER.
